UNITED STATES PATENT OFFICE

WILHELM NOELTE, OF HOBOKEN, NEW JERSEY.

LATCH.

SPECIFICATION forming part of Letters Patent No. 372,815, dated November 8, 1887.

Application filed July 7, 1887. Serial No. 243,613. (No model.)

To all whom it may concern:

Be it known that I, WILHELM NOELTE, a citizen of Germany, residing in Hoboken, Hudson county, State of New Jersey, have invented a new and Improved Latch, of which the following is a specification.

This invention relates to a latch having but a single bolt. This bolt may be thrown out of the case to a greater or less extent. It is operated by the ordinary turning-knob when it projects but little out of the latch-case, and it may then be shot out to a greater extent by the use of the key. Thus the same bolt acts as a latch and as a locking-bolt. The latch-case is also provided with a slide similar to a latch, and which enables the bolt to be locked in its distended position from the inside of the room without a key.

The invention consists in the various features of improvement more fully pointed out in the claim.

In the accompanying drawings, Figure 1 is a face view of the latch with the front plate removed, showing the bolt but partially shot out. Fig. 2 is a similar view with the bolt entirely shot out. Fig. 3 is a longitudinal section on the line *x x*, Fig. 2.

The letter *a* represents the latch-case, in which slides the bolt *b*, which is provided at its rear end with a pin, *c*. This pin enters an angular slot, *d'*, on a lever, *d*, pivoted at *d'* and slotted at *d*, for the reception of the knob-spindle *e*.

f is a stop placed against the lower side of the bolt and near its rear edge when the bolt is entirely shot out, as in Fig. 2. Springs *g*, *g'* bear, respectively, against shoulders on the front and rear of the bolt *b*.

h are the tumblers, pivoted at *h'* and provided with springs *h* abutting against pin *h*. The tumblers have H-shaped slots that admit a pin, *i*, secured to the bolt *b*. Noses or projections *h* on the tumblers may be depressed by a flat plate, *j*, attached to and revolved by a button, *j'*. This button projects outside of the latch-plate and is accessible from the interior of the room.

k is a slide or button attached to the bolt *b*, and also projecting into the room through a slot in the latch-plate. By means of this slide the bolt may be shot in or out if the tumblers are cleared without the use of a key.

The operation of the device is as follows: The parts being in the position shown in Fig. 55 1, the latch is adapted to be operated by the

knob *e* of the knob-spindle *e*. In this position the pin *c* occupies the rear branch of the angular slot *d'*, and by revolving the knob *e* the bolt may be drawn entirely into the case. On the release of the knob the spring *g'* will 60 push the bolt out to a short extent, limited by the pin *i*, bearing against the rear shoulder, *i'*, of the tumbler-slot. When the latch is to be locked by the key, the latter is introduced opposite hole *m* and will lift the 65 tumblers so that the pin *i* clears shoulder *i'*, when the bolt may be shot out to its greatest extent, as in Fig. 2. In this position the pin *i* will have entered the forward part of the tumbler-slots, and the shoulder *i* will prevent the bolt from being withdrawn without the use of the key. As the bolt has been shot out, the pin *c* will have been drawn forward, and after having passed the bend in slot *d'* will have oscillated the lever *d* to occupy the 70 position shown in Fig. 2. In this position the knob *e* cannot be revolved, owing to the stop *f* being nearly or exactly opposite pin *c*, and thus the latch could not be opened though there were no tumblers. To reopen 75 the latch, the key is applied to raise the tumblers, throw the bolt back into the position shown in Fig. 1, and to swing the lever *d* backward on its pivot.

If the bolt is to be shot out from the interior of the room by means of the slide *k*, the button *j'* is first revolved, when the plate *j* will depress noses *h*, and thus cause the tumblers *h* to be oscillated sufficiently to cause the pin *i* to clear shoulder *i'*. The spring *g'* 80 will then throw the bolt forward sufficiently to cause the pin *i* to enter the narrow central part of the tumbler-slot, after which there is no obstacle in the way of shooting the bolt out entirely by the slide *k*. To withdraw the 85 bolt, the button *j'* is again revolved to cause the oscillation of the tumblers and the consequent clearing of the shoulders *i* by pin *i*, aided by spring *g*, when the bolt can be moved inward by the slide *k*.

What I claim is—

The combination of bolt *b*, having pins *i c*, with the slotted lever *d*, spindle *e*, stop *f*, springs *g*, *g'*, tumblers *h*, having noses *h*, and with the springs *h*, plate *j*, and slide *k*, substantially as specified.

WILHELM NOELTE.
